United States Patent Office

Des. 191,762
Patented Nov. 14, 1961

191,762

LIGHTING FIXTURE

Emanuel Allan Rothman, Brooklyn, N.Y., assignor to
McPhilben Lighting Inc., Brooklyn, N.Y., a corpora-
tion of New York

Filed May 19, 1960, Ser. No. 60,648

Term of patent 14 years

(Cl. D48—4)

FIG. 1

FIG. 2

FIG. 3

FIG. 4

FIG. 1 is a perspective view of a lighting fixture showing my new design;

FIG. 2 is a front elevation thereof;

FIG. 3 is a bottom plan thereof;

FIG. 4 is an elevation thereof as seen from the right of FIG. 2.

The dominant features of my design reside in the portions shown in full lines.

I claim:

The ornamental design for a lighting fixture, as shown and described.
